UNITED STATES PATENT OFFICE.

HERMANN LEMP, OF LYNN, MASSACHUSETTS, ASSIGNOR, BY MESNE ASSIGNMENTS, TO
GENERAL ELECTRIC COMPANY, A CORPORATION OF NEW YORK.

KEROSENE-BURNER.

969,545.

Specification of Letters Patent. Patented Sept. 6, 1910.

Application filed August 5, 1903. Serial No. 168,297.

To all whom it may concern:

Be it known that I, HERMANN LEMP, a citizen of the United States, residing at Lynn, county of Essex, State of Massachusetts, have invented certain new and useful Improvements in Kerosene-Burners, of which the following is a specification.

The use of kerosene as fuel for burners of the Bunsen type, such as are commonly used in connection with automobile steam generators, is attended with difficulty. This is due largely to the fact that kerosene requires a high degree of temperature to effect its vaporization and to maintain it in a gaseous state. Condensation of the vapor takes place rapidly under cooling influences. If, for any reason, the condensed kerosene is injected into the burner as a liquid, its presence in the burner will cause smoke and smell and seriously retard the lighting of the burner.

In the common form of vapor burner, a pilot burner is employed for the purpose of preliminary starting or restarting the main burner of the boiler. The pilot burner is generally situated in the combustion chamber of the boiler. In this position it subserves two functions, that of heating the vaporizer and of effecting the ignition of the vapor when a sufficient amount has been generated to begin issuing from the vapor apertures of the burner. By this arrangement, however, the flame of the pilot burner is restricted to a limited portion of the vaporizing system so that remote portions thereof become cold. This is particularly objectionable for the reason that when the pilot burner alone is in operation the flame heats only the vaporizer while the tube connection leading therefrom to the injector, and located outside of the boiler and burner casing, fails to be heated. The resulting effect is that condensation of kerosene vapor occurs in the tube connection. Consequently when it is desired to restart the main burner the fresh supply of vapor generated in the vaporizer will, when injected, entrain a certain amount of liquid kerosene with it. Thus the liquid kerosene is forced into the injector tube and mixing chamber of the main burner and collects in the same. As the liquid is of a temperature lower than that of the ensuing vapor, there is a tendency to further condensation of the vapor.

Under these conditions, with the presence of liquid kerosene in the burner, the ignition of the vapor is considerably retarded and the burning attended with odor and smoke.

The object of my invention is to overcome the objections above named. Therefore, in the means for accomplishing this, the pilot burner is arranged in such a position that its flame impinges upon the injector nozzle and the connection between it and the vaporizer. The flame of the pilot burner is permitted to extend into the combustion chamber of the boiler so as to effect the lighting of the main burner. Thus the function of the pilot burner is to heat the injector and its tube or connection sufficiently to cause complete vaporization of the kerosene for starting purposes. It thereby prevents the condensation of vapor into liquid kerosene and its injection into the injector tube and mixing chamber of the burner.

The details of arrangement will be more fully described hereinafter and finally set forth in the claims.

In the accompanying drawing, which illustrates one embodiment of my invention, Figure 1 shows a section of the combustion chamber of a boiler and main burner, with a pilot burner applied thereto; Fig. 2 is a detail view of the pilot burner; and Fig. 3 is a modified form of pilot burner attached to the boiler.

The main burner is of the injector or Bunsen type, such as is used in connection with steam generators for automobiles. My invention has to do particularly with a pilot burner and is adapted to be applied to any kind of burner operating upon the injector principle for mixing the kerosene vapor with air.

Referring to the drawing, 1 represents the combustion chamber of a steam generator, 2 the main burner of the flat chamber kind, having the usual air flues 3 and gas perforations 4. The burner 2 is provided with the injector tube 5 arranged radially under the same in a horizontal position. An injector 6 is arranged exteriorly of the boiler and disposed centrally in line with the mouth of the injector tube. The injector is controlled by a suitable needle valve 7. A vapor-carrying tube 8 connects the injector with a main vaporizer 9. This vaporizer is arranged in the combustion chamber so as to be heated

by the flame of the main burner. Obviously suitable connection for the vaporizer 9 is made with a source of fuel supply, and the feed of the fuel may be after any approved 5 manner.

Instead of arranging the pilot burner in the combustion chamber of the boiler casing according to the common practice, the pilot burner in the present case is arranged outside 10 of the boiler. The pilot burner 10 is supported adjacent the injector so that its flame plays upon the injector and vapor tube. In order to concentrate the flame upon the injector and vapor tube, a heating flue 15 or chimney 11 incloses these members. This heating flue is secured to the shell or casing of the boiler and communicates with the combustion chamber at one end. For this latter purpose the shell of the boiler is provided with an opening 12 through which the vapor tube extends to connect with the main vaporizer. The opening 12 is of sufficiently large diameter to permit free communication between the heating flue and the 20 combustion chamber, so that the flame and burned gases of the pilot burner can pass into the combustion chamber. In order to protect the nozzle 13 of the injector 6 from the flame of the pilot burner, the injector is 25 arranged transversely in the heating tube, with the nozzle projecting snugly through the wall. The needle valve stem also passes through the wall of the heating flue.

The pilot burner consists of a vaporizing 30 tube or vaporizer 14 suitably coiled to produce a large heating surface in a small compass, and the end of the tube terminates in a nozzle 15. The nozzle 15 is preferably turned toward the coiled portion of the tube, 35 so that the flame from the nozzle will impinge upon the vaporizing tube. Pipe connection 16 is had with a source of liquid fuel supply, this connection being preferably independent of the fuel supply pipe 40 leading to the main vaporizer. A needle valve 17 is provided for controlling the fuel supply to the pilot burner. At the outer end of the heating flue a starting cup 18 is arranged in close proximity to the valve and 45 vaporizing tube of the pilot burner.

In operation, the starting cup is provided 50 with a volatile liquid such as alcohol or gasolene, and the same is lighted. The flame produced thereby serves to start the pilot burner. The vaporizing tube becomes 55 intensely heated, and as the kerosene is fed to the same by opening the needle valve 17, vapor is immediately generated. This vapor or gas issues from the nozzle and ignites by 60 the flame rising from the starting cap. The pilot flame thereafter vaporizes its own fuel and continues burning as long as the needle valve is opened. The flame of the pilot burner passes up through the heating tube, 65 and heats the injector and vapor tube suf-

ficiently to cause vaporization of the kerosene for supplying the main burner. Upon opening the needle valve 7 of the injector the vapor issues into the injector tube, becoming mixed with air, and then the mixture of vapor and air passes into the chamber of the burner from which it issues through the perforations 4 into the combustion chamber. In the combustion chamber the gas ignites by means of the flame of the 75 pilot burner.

As shown in Fig. 3, the modified embodiment of my invention comprises, in general terms, a main vaporizer 19, an injector 20, an injector tube 21, a main burner 22, a 80 pilot burner 23, and a heating flue 24. The essential difference between the modified construction and that already described is that the connecting tube between the main vaporizer and injector is so shortened as to 85 be substantially dispensed with. The flame of the pilot burner is adapted to impinge upon the injector and the adjacent end of said vaporizer. The pilot burner is of the same construction, but is disposed horizontally, with the injector vertical. For the starting cup is substituted a dished portion 90 formed in the heating flue. In order to meet this new position of the injector, the injector tube is upturned at its outer end, as 95 is clearly shown.

The operation of the modified form of pilot burner is similar to that of the form hereinbefore described.

It will be noted that by arranging the 100 pilot burner adjacent the nozzle of the injector the liquid kerosene positively vaporizes before it passes out of the nozzle. Thereby the injection of liquid into the main burner is prevented, with its attending 105 objections of retarding the lighting and causing smoke and odor during burning.

In accordance with the provisions of the patent statutes I have described the principle of operation of my invention, together 110 with the apparatus which I now consider to be the best embodiment thereof; but I desire to have it understood that the apparatus shown is only illustrative and that the invention can be carried out by other means. 115

What I claim as new, and desire to secure by Letters Patent of the United States, is,—

1. The combination of a burner of the chamber type, a casing adjacent the same 120 which forms a combustion chamber, a vaporizer arranged in the chamber, an injector exterior to the chamber which receives vapor from the vaporizer and delivers it to the burner, an open ended flue in the walls of which the injector is mounted with its nozzle outside said walls, said flue opening to the air at its outer end and having its inner end entering the combustion chamber adjacent one end of the vaporizer, a conduit 125 located within the flue which conveys fuel

vapor from the vaporizer to the injector, a pilot burner in the flue between the outer end and the injector, which directs its flame against the injector and also along the flue 5 into the chamber to heat the vaporizer, and a vaporizer for the pilot burner which is heated by the flame thereof.

2. A burner system comprising a main burner, a vaporizer arranged above the 10 burner, a casing for the vaporizer which forms a combustion chamber, and an injector receiving vapor from the vaporizer which is exterior to the casing, in combination with an auxiliary or pilot burner which 15 comprises a nozzle, a vaporizing coil connected with the nozzle which is heated by the pilot flame, a flue in the walls of which the injector is mounted with its nozzle projecting beyond said walls, an injector tube 20 leading from a point opposite the injector nozzle to the main burner, said flue surrounding the auxiliary burner, directing the pilot flame on the injector and entering the casing opposite the main vaporizer to discharge 25 its contents over said vaporizer, a conduit extending along the median line of the flue between the main vaporizer and the injector, and a starting cup for heating the auxiliary system which is arranged adjacent 30 the outer end of the flue to receive fuel from said pilot burner nozzle.

3. In combination, a casing, a main burner of the chamber type attached to the lower end of the casing, a vaporizer arranged 35 in the casing above the burner, a pilot burner, an injector for the main burner which receives vapor from the vaporizer and is arranged between the latter and the pilot burner, a vaporizer for the pilot 40 burner which is disposed between the same and the injector to be heated by the pilot flame, a flue in the walls of which the injector is mounted transversely of the flue passage with its nozzle projecting from one 45 of said walls, said flue also surrounding the pilot burner and its vaporizer and entering the casing adjacent the main vaporizer to discharge 50 its contents over said vaporizer, a conduit extending along the median line of the flue between the main vaporizer and the injector, and a valve for the injector, the

handle of which projects from the walls of the flue opposite the nozzle.

4. A burner system, comprising a main burner, a casing, a main vaporizer within 55 the casing which is heated by the burner, an injector for supplying vapor to the burner, and a tube between said main vaporizer and the injector, the latter being exterior to the casing, in combination with a 60 pilot burner comprising a vapor discharging nozzle which is located adjacent to and directs its flame against the injector and along said tube, a vaporizer connected with and supplying said nozzle which is heated 65 by the pilot flame, and a flue along the median line of which the tube between the injector and the main vaporizer extends, said flue surrounding the pilot burner system and the injector and entering the casing 70 opposite said main vaporizer.

5. The combination of a main burner, a casing extending upwardly from the burner, a main vaporizer arranged in the casing for supplying the burner, the casing having an 75 opening adjacent said main vaporizer, an injector discharging fuel vapor from the main vaporizer to the burner, a tubular flue in the walls of which the injector is mounted transversely of the flue passage with its 80 nozzle projecting from the walls thereof, an injector tube leading from a point opposite the nozzle to the main burner, said flue being open to the atmosphere at one end and having its other end connected with the 85 opening in the casing, a tube extending along the median line of the flue between the main vaporizer and the injector to supply the latter with fuel, a pilot burner arranged in the open end of the flue which 90 sends its flame along said flue over the injector and the tube and through the opening in the casing to contact with the main vaporizer, and a vaporizer for the pilot burner which is heated by its flame. 95

In witness whereof I have hereunto set my hand this third day of August 1903.
